UNITED STATES PATENT OFFICE.

JAMES H. CARTER, OF CHICAGO, ILLINOIS.

FLAT FOR EGG-CASES.

1,293,331.

Specification of Letters Patent.

Patented Feb. 4, 1919.

Application filed July 8, 1916. Serial No. 108,106.

To all whom it may concern:

Be it known that I, JAMES H. CARTER, a citizen of the United States, and a resident of the city of Chicago, county of Cook, and

5 State of Illinois, have invented certain new and useful Improvements in Flats for Egg-Cases, of which the following is a specification.

10 My invention has relation to containers or cases for the storage and shipment of eggs and more particularly to the member known as the "flat" that is employed in cellular cases for the purpose of dividing one unit of cells or compartments from those 15 above or below the same.

One of the objects of my invention is the provision of a flat that is adapted to retain both the upper and the lower edges of each wall of both upper and lower cells or egg 20 compartments in proper position so as to prevent movement of the rows of eggs stored therein and the consequent breakage of a quantity of eggs in rough handling. Another object of my invention is the provision 25 of an egg-case flat that may be stamped from a single piece of fiber-board by one operation which forms projections upon both faces thereof so that a single flat will be capable 30 of acting in the capacity of a retainer for the lower edges of the cellular walls of an upper unit and at the same time perform the same function for the upper edges of a unit disposed next below said flat. Further objects of my invention are to provide a flat 35 for egg-cases that is simple to manipulate, effective in operation and comparatively inexpensive to manufacture.

I prefer to accomplish the divers objects 40 of my invention by the means and in the manner hereinafter described and as more particularly pointed out in the claims, reference being had to the accompanying drawings forming a part of this specification, wherein—

45 Figure 1 is a fragmentary perspective view of a corner of my improved flat for egg-cases, with the cellular units removed to better illustrate the disposition of the projections.

50 Fig. 2 is a top plan of the fragment illustrated in Fig. 1.

Fig. 3 is a transverse vertical section taken on line 3—3 of Fig. 2, showing portions of the cellular units in position.

55 Fig. 4 is a sectional view of a slightly modified construction of my invention, and

Fig. 5 is a top plan of a corner fragment of the modified structure illustrated in Fig. 4.

Referring more particularly to Figs. 1, 2 60 and 3 of the drawings, it will be observed the flat 10 preferably comprises a substantially rectangular strip of board, cardboard, fiber-board, or the like, that is adapted, as will be seen in Fig. 3, to be disposed between 65 the divers cellular units for the purpose of separating or spacing the latter and at the same time to form both the bottom and top walls of adjacent superposed cells. The cellular units are preferably constructed of 70 the usual longitudinal and transverse intersecting walls 11 and 12, that are provided with any desired interlocking means for the purpose of retaining them in substantially upright position when in use and whereby 75 they may be readily collapsed or folded, as is well known, when not in use. The cells formed by these walls 11 and 12 are substantially rectangular in outline, and in order to provide means for preventing their 80 upper and lower edges from being moved laterally, I have provided the flat 10 with a plurality of upwardly and downwardly projecting tongues or flaps 13 and 14 respectively, that are constructed and arranged in 85 the following manner: In order to shape these tongues or flaps, suitable crescent or segmental shaped cuts are made in the blank forming the flat and the material included within the contour of the cuts is bent or 90 folded upwardly or downwardly, as the case may be. The tongues 13 which are adapted to project upwardly above the surface of the flat, are positioned, as shown in Figs. 1 and 2 of the drawings, so as to engage the 95 walls of the cells intermediate the points where the walls intersect each other and when the flat 10 is interposed between two superimposed units, these tongues 13 will engage each wall of a cell upon the opposite 100 sides at the lower edge thereof and thus prevent that portion of the wall from being moved any great distance laterally. The downwardly projecting tongues or flaps 14 are of substantially the same shape as the 105 tongues or flaps 13 and are bent downwardly from the underside of the flat so as to engage the upper edges of the under unit at the point of intersection between the walls 11 and 12 and thus prevent lateral movement of 110 the upper edges of the cell. It will thus be seen that each cell of a single unit is pro-

tected against lateral movement of its walls by the downwardly projecting tongues or flaps 14 of the upper flat, and also by the upwardly projecting tongues or flaps 13 of the lower flat.

In Figs. 4 and 5 I have shown a slightly modified construction of my invention. The flat 15 is preferably twice the length of the flat 10 shown in the preferred construction, 10 and the projections preferably comprise tongues or flaps 16 that are of segmental shape in outline and are punched so that all project upwardly from one and the same surface of the flat. These tongues or flaps 15 16 are positioned so as to engage the walls of the cells intermediate the intersections, and when the flat is ready for use the same is folded transversely, as at 17 (Fig. 4) so as to dispose the flaps or tongues 16 in position 20 to project both upwardly and downwardly from the folded flat and thereby engage the upper and lower edges of the respective cell walls.

While I have herein described and illustrated certain specific means for carrying out my invention, it of course will be obvious to others skilled in the art to which my invention pertains, that divers modifications or refinements thereof are possible without materially departing from the spirit of my invention. I therefore desire it understood that all such changes and modifications are contemplated within the scope of my invention as expressed in the appended claims.

35 What I claim as new is:—

1. In a device of the kind described the combination with a plurality of cellular units, each unit formed of strips intersecting each other to form the four walls of each 40 cell, of flats dividing and separating said units, each flat provided with a plurality of projections arranged in intersecting rows

and so disposed that four oppositely arranged projections are adapted to engage the respective four walls of each cell adjacent thereto and at points intermediate the intersections of the wall strips.

2. In a device of the kind described the combination with a plurality of cellular units each unit formed of strips intersecting each other to form the four walls of each cell, of flats dividing and separating said units, each flat provided with tongues projecting from both sides thereof, the tongues projecting from one side of said flat being in 55 intersecting rows and between the points of intersection adapted to engage all the walls of each cell between the corners of said cells, and the tongues projecting from the other side of said flat being in intersecting rows 60 in the corners of the intersections and adapted to engage all the walls of each cell at the corners of each cell.

3. In a device of the kind described the combination with a plurality of cellular units each formed of a plurality of intersecting strips, of flats interposed between said units, each flat comprising a strip of material provided with tongues projecting from one side, said strip adapted to be 70 folded transversely mediate its ends so as to provide a flat having tongues projecting from opposite sides thereof, said tongues arranged in rectangular figures whereby the four walls of each cell are engaged at their 75 upper edges intermediate their corners and at each corner of their upper edges.

Signed at Chicago, county of Cook, and State of Illinois, this 2d day of June, 1916.

JAMES H. CARTER.
